Attorneys,

UNITED STATES PATENT OFFICE.

LUCINDA HARVEY, OF CANON CITY, COLORADO.

MILK-CAN.

SPECIFICATION forming part of Letters Patent No. 746,328, dated December 8, 1903.

Application filed June 23, 1903. Serial No. 162,785. (No model.)

To all whom it may concern:

Be it known that I, LUCINDA HARVEY, a citizen of the United States, residing at Canon City, in the county of Fremont and State of Colorado, have invented certain new and useful Improvements in Milk-Cans; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 My invention relates to milk-cans, but more particularly to the caps or covers therefor, and has for its object to provide a device of this class which will effectually form an air-tight closure.

20 A further object of my invention is to provide a milk-can of simple construction wherein the milk is prevented from coming in contact with the cap or cover proper.

With these objects in view my invention 25 consists in the novel arrangement of the cap or top in combination with the paper disk.

My invention further consists in certain other novel features of construction and in combination of parts, which will be first fully 30 described and afterward specifically pointed out in the appended claims.

Referring to the accompanying drawings, Figure 1 is an elevation of a milk-can and top constructed in accordance with my invention. Fig. 2 is an elevation, partly in section, showing top in position.

Like numerals of reference indicate the same parts throughout both figures, in which—

40 1 is the milk-can, provided with reinforcements 2 at the breast and at the bottom.

3 indicates the neck of the can, and 4 a flaring mouth, said neck being provided with an annular bead 5.

45 6 indicates the cap or cover, which is provided with the usual handle 7, the perpendicular annular wall 8 of said cap being provided with slight kerfs or incisions 9 at the bottom thereof, and the lower portion of said 50 wall is provided with an annular bead 10.

11 indicates a disk of paper, cardboard, or other suitable material which is provided

with wire loops 12 or other suitable grasping means.

An annular flange 13 is provided in the interior of the neck below the annular bead, forming a seat for said disk.

Having thus described the several parts of my invention, its operation is as follows: The can having been filled, the disk is inserted in the neck of the can and is held in position by the annular bead 5 in said neck. The cap is then inserted, the kerfs or cuts in the bottom thereof allowing the bead to spring in, so that the annular vertical wall thereof will pass into the neck of the can. The cap is thus inserted until the bead 10 registers with the bead in the can, the bottom of said bead 10 coming in contact with the disk, holding the same in position within the head 5 and in close contact with the disk-seat 13, thus forming an air-tight closure. As will be seen from Fig. 2, a hollow compartment 14 above said disk incloses the wire-loops or other grasping means and protects the same. This compartment, which is also practically air-tight, forms a further seal against the action of the atmosphere on the milk.

As is well known, milk-cans of approved type, by reason of the friction between the cap and the neck of the can, become blackened, and the milk frequently slushes up against said blackened surface during transportation, which has the effect of darkening the same and giving to it a dirty appearance. With my construction, however, this slushing of the milk into and against the metal cap is entirely obviated.

Having thus set forth my invention, I do not wish to be understood as limiting myself to the exact construction herein set forth, as various slight changes may be made therein which would fall within the limit and scope of my invention—as, for instance, the kerfs or cuts in the bead of the cap could be dispensed with and other minor changes could be made—and I consider myself clearly entitled to all such modifications which fall within the limit and scope of the following claims.

What I claim as new, and desire to secure by Letters Patent of the United States, is—

1. In a milk-can the combination with the neck thereof of an annular bead therein, a cap having an annular wall and provided with a

bead thereon having kerfs or cuts therein, a disk adapted to enter the bead in said neck, and to be held therein by the bead on said cap, and a seat for said disk substantially as described.

2. In a milk-can, the combination with the neck thereof of an annular bead therein, a cap having an annular wall and provided with a bead thereon, a disk adapted to enter the said bead in said neck, and the said bead

on said cap, being adapted to spring into the said bead in said neck and hold said disk firmly in position when said cap is inserted in the can.

In testimony whereof I affix my signature 15 in presence of two witnesses.

LUCINDA HARVEY.
